ABSTRACT: Apparatus for supplying an additive vapor into the fuel-air mixture of an internal combustion engine includes a reservoir for a liquid solution including methanol. The reservoir is connected to the engine by a flexible conduit defining a suction line connected to the primary vacuum inlet of the engine. The reservoir includes an inlet conduit for bubbling air through the solution to produce a vapor in the upper reservoir chamber which is drawn into the engine inlet through the suction conduit. A check valve in the suction line maintains the reduced pressure in the reservoir during times of increased pressure in the engine primary vacuum inlet.

VAPOR INJECTOR

BACKGROUND OF THE INVENTION

This application is a continuation-in-part of my copending application Ser. No. 734,834 filed May 6, 1968 for Vapor Injector, now abandoned.

This invention relates to internal combustion engines and more particularly to apparatus for injecting vapor into the engine inlet improving the performance and efficiency of internal combustion engines.

The inefficiency of internal combustion engines is well known and this has been a major factor in air pollution due to the presence of unburned or partially burned fuel in the exhaust from the engines of automobiles and other vehicles. In recent years, the problem has become so severe that federal legislation has been passed requiring automotive manufacturers to equip all new cars with "smog eliminators." Numerous methods and apparatus have been proposed heretofore for reducing air pollution caused by internal combustion engines; however, none of the prior art devices have been entirely satisfactory. Filtering devices have been employed to remove unburned fuel from automotive exhaust, before the exhaust was discharged into the atmosphere. However, such devices have not been entirely effective and often cause a significant reduction in the performance of the engine. Other devices, such as superchargers, have improved the performance of the engine but have not greatly reduced the pollution problem. Furthermore, many of the prior art devices have been complex and expensive and have been difficult to install and maintain.

These disadvantages of the prior art are overcome with the present invention; and apparatus is provided whereby the efficiency and performance of internal combustion engines are both improved substantially. Moreover, the device of the present invention is simple and inexpensive, can be installed easily and requires virtually no maintenance.

The advantages of the present invention are preferably attained by providing an aqueous solution of methanol and apparatus for vaporizing the solution and injecting the vapor into the cylinders of an internal combustion engine during operation of the engine to produce more complete combustion of fuel.

Accordingly it is an object of the present invention to provide improved apparatus for increasing the efficiency of internal combustion engines.

Another object of the present invention is to provide improved apparatus for increasing the performance of internal combustion engines.

A further object of the present invention is to provide improved apparatus for reducing air polluting emissions from internal combustion engines while simultaneously improving the performance of such engines.

A still further object is to provide improved apparatus adapted to be readily connected to an internal combustion engine for improving the performance thereof.

A specific object of the present invention is to provide improved apparatus for forming a vapor of an aqueous solution of methanol alcohol and injecting the vapor into the cylinders of an internal combustion engine during operation of the engine.

These objects are accomplished by apparatus for connection to the suction inlet of an internal combustion engine, the apparatus including a reservoir for containing a solution to be vaporized, vaporizing means for flowing air from the exterior of the reservoir through the solution to form a vapor in the upper portion of the reservoir chamber, and the upper chamber portion of the reservoir being communicated with the engine suction inlet through a suction line, the flow of air through the reservoir being effected by the reduced pressure within the reservoir. Check valve means in the reservoir suction line prevents flow from the engine to the reservoir.

DRAWINGS

The novel features of the invention, as well as additional objects and advantages thereof, will be understood more fully from the following description when read in connection with the accompanying drawings, in which:

FIG. 1 is a diagrammatic and elevation view of an internal combustion engine and of associated vapor injecting apparatus; and

FIG. 2 is a detail sectional view of the vacuum line connector and check valve shown in FIG. 1.

DESCRIPTION OF THE PREFERRED EMBODIMENT

Referring to the drawing, FIG. 1 includes a diagrammatic illustration of an automobile-type gasoline engine. As shown in FIG. 1, carburetor 6 seated on top of the engine block including an inlet passage 7 and valve 8 through which combustion air flows from the air filter into the inlet manifold of the engine, gasoline being mixed with the air in the carburetor to provide a combustible fuel-air mixture. A passage 9 through the carburetor wall communicates with the carburetor throat 7 to define a primary vacuum inlet which serves as a source of vacuum or reduced pressure for various engine functions or for the operation of accessories.

The engine diagram also shows an exhaust valve 11, the stem of which extends through the cylinder head 10 to the exterior thereof, and a rocker arm 12 and a pushrod 13. The rocker arms and associated mechanism for the engine are enclosed by a valve cover 14 which is normally sealed to the cylinder head by a sealing gasket.

Since exhaust gases and fumes may leak around the valve stem into the chamber enclosed by the valve cover 14, it is conventional practice to evacuate these chambers by connecting these chambers to the above mentioned primary vacuum inlet 9. This is part of the positive crankcase ventilation system by means of which engine fumes and vapors are returned to the engine inlet to afford further opportunity for complete combustion. In this drawing, the valve cover return line includes a conduit 15, a portion of a T-connector 16, a conduit 17 and a fitting 18 fitted into the vacuum inlet passage 8. The conduits 15 and 17 may be flexible hoses of rubber or like material.

In accordance with the present invention, a primary vacuum inlet 9 is employed to introduce into the engine, for admixture with the fuel-air mixture, vapors which have the effect of improving the combustion and performance of the engine. It has been discovered that vapors from an aqueous solution which includes methanol as a principle ingredient to produce the desired beneficial results in the engine.

As shown principally in FIG. 1, apparatus for supplying vapor to the engine includes a reservoir 21 consisting of an open topped vessel 22, fabricated of high silica glass for example, and a closure cap 23 fabricated of cast aluminum for example. The closure cap may be threaded on to the container in a conventional manner and sealed thereto with a suitable gasket. The closure cap is provided with a filler opening, closed by means of a suitable plug 24.

For admitting air into the reservoir 21, the closure cap 23 is provided with an inlet passage and an associated control valve 26, such as an adjustable needle valve, for controlling the flow of air through the passage. An inlet conduit 27 communicates with the inlet control valve 26 and extends to a point adjacent the bottom of the reservoir, terminating in an aerator device 28 for breaking up the air into numerous bubbles which pass upward through the solution in the reservoir to the upper reservoir chamber defined above the liquid level.

The closure cap 23 is provided with a suitable boss 31 having a passage therethrough, to which is conveniently connected a suction conduit 32 for communicating the upper reservoir chamber with the primary vacuum inlet 9. For this purpose, in the preferred form of the invention, the suction conduit 32 which may be a hose of rubber or similar material, is connected to one branch of the T-connector 16 in the valve

cover evacuation line. The suction conduit 32 includes a check valve to prevent the flow of vapor from the engine into the reservoir 21; and this check valve may be conveniently provided in the T-coupling 16 as will be described.

The T-coupling 16 is shown in FIG. 2 apart from the flexible conduits which may be connected to it. This coupling includes a principal body portion 35 which is elongated and has oppositely projecting nipples, each provided with spaced groups of annular serrations 36 and 37. The inner serrations 36, which are closer to the body 35, are of larger diameter to accommodate a $\frac{1}{2}$ -inch I.D. flexible hose, for example, while the outer serrations 37 are of smaller diameter to accommodate a $\frac{3}{8}$ inch I.D. flexible hose, for example. In this sense then the connector 16 is a universal connector adapted to be inserted into an existing vacuum line of an engine for use with several sizes of hoses. The connector further includes a laterally projecting shank 38 which defines, with a valve seat portion 39, a check valve housing enclosing a ball closure member 40 coacting with the valve seat 41. The valve seat portion 39 of the connector includes a serrated nipple 42 to which the reservoir suction line 32 is connected.

During normal flow conditions, when the vapor flows from the nipple 42 through the check valve and into the connector body 35, the ball closure 40 is urged against small projections 50 surrounding the flow passage through the shank 38 which permits flow around the ball closure member. Should there be any reversing of the pressure differential, whereby the pressure on the reservoir side of the check valve should be less than that on the engine side, the check valve is dimensioned so that this reverse flow will effect an immediate seating of the ball closure member 40 on the seat 41 to prevent such reverse flow.

In operation, the vacuum produced in the engine suction inlet 9 withdraws air from the reservoir to reduce pressure therein. This results in air flow into the reservoir through the adjustable inlet control valve 26, this air flowing through the inlet conduit 27 and aerator 28 to produce numerous air bubbles which flow upward through the solution in the reservoir. In doing this, the air becomes mixed with the solution and forms a vapor of this solution which collects in the upper chamber portion of the reservoir 21. This vapor is drawn from the reservoir through the suction conduit 32, the check valve and the T-connector 16, and the connector 17 to mix with the fuel-air mixture flowing through the carburetor throat 7 into the engine intake manifold.

Thereafter, during each charging stroke of the engine, a mixture of the fuel-air mixture and the additive vapor will be drawn into the engine cylinders to be compressed and burned in a conventional manner. It has been found that the introduction of the vapor of the aqueous solution of methanol causes a significantly higher temperature of combustion than is achieved with a conventional fuel-air mixture. As a result, virtually 100 percent of the fuel in the fuel-air vapor mixture is burned, whereas only about 55 percent of the fuel in conventional fuel-air mixture is burned. Because of the more efficiently burning of the fuel with the vapor additive, the performance of the engine is improved, and the engine runs more smoothly and produces substantially more power than does the same engine when operated with conventional fuel-air mixtures. Furthermore, because of more efficient utilization of fuel, it is found that spark plug fouling and oil contamination are virtually eliminated resulting in longer life for the en-

gine. In addition, air pollution problems are overcome or substantially reduced since substantially all of the fuel is burned and substantially no unburned or partially burned hydrocarbons remain to be discharged in the engine exhaust.

The combination of a check valve with the described vapor producing device provides a number of advantages. The danger of damaging the apparatus, due to a sharply increased pressure within the reservoir produced by a backfire for example, is obviated. Such a pressure increase might rupture the container 22, or produce the inconvenience of blowing and losing the filler plug 24 or rupturing the inlet conduit 32. The check valve provides the additional advantage of maintaining the less-than-ambient pressure within the reservoir at times of increased pressures within the carburetor throat 7, such as at times of engine acceleration. At such times, the pressure in the suction inlet 9 may rise above the pressure within the reservoir 21 to produce a reverse flow to unnecessarily and undesirably increase the pressure within the reservoir. Furthermore, if such reverse flow is permitted through the conduit 32, vapors and fumes flowing through the conduit 15 from the valve cover 14 could then flow into the reservoir 21, resulting in surface contamination of the solution within the reservoir which may significantly retard the production of the desired vapor within the reservoir. With a check valve designed to seat instantaneously with any reverse pressure differential, these disadvantages are obviated. The apparatus described is adapted to be readily mounted in a motor vehicle in operative association with the vehicle engine.

I claim:

30. 1. Vapor injecting apparatus for use in combination with an internal combustion engine including a carburetor having an air passage and a throttle valve positioned in said air passage producing a region of reduced pressure in the air passage downstream of the throttle valve and a first line providing communication between the region of reduced pressure and a crankcase ventilation system of the engine that comprises a T-connector connected into said first line and having a branch outlet, a closed reservoir for containing a supply of volatile liquid additive with a vapor chamber above the liquid additive, 35 means for admitting air into said reservoir below the liquid level at a metered rate, a second line connected between the branch outlet of the T-connector and the vapor chamber portion of the reservoir and check valve means positioned for permitting normal free flow of vapor from the vapor chamber of the reservoir into the region of reduced pressure and restricting undesired flow of fluid from the first line into the reservoir upon abnormal operation of the engine to prevent an excessive pressure being produced in the reservoir.

2. Vapor injecting apparatus as defined in claim 1 wherein 50 said means for admitting air into said reservoir at a metered rate comprises adjustable valve means positioned in an inlet conduit of said reservoir for controlling the flow of air through said inlet conduit.

3. An internal combustion engine as set forth in claim 1 55 wherein said check valve means is disposed in the branch outlet of said T-connector.

4. An internal combustion engine as set forth in claim 3 wherein said T-connector includes terminal nipples for attachment to flexible conduits; and wherein one or more of said nipples include serrated portions of different diameters for accommodating flexible conduits having different internal diameters.
